UNITED STATES PATENT OFFICE.

ISIDOR KITSEE, OF PHILADELPHIA, PENNSYLVANIA.

TELEGRAPHIC SENDING DEVICE.

No. 824,028.

Specification of Letters Patent.

Patented June 19, 1906.

Application filed January 27, 1903. Serial No. 140,718.

To all whom it may concern:

Be it known that I, ISIDOR KITSEE, of Philadelphia, in the county of Philadelphia and State of Pennsylvania, have invented certain 5 new and useful Improvements in Telegraphic Sending Devices, of which the following is a specification.

In the drawings I have selected as the best method of explaining my invention the 10 adaptation thereof to a use which I now directly contemplate—to wit, the signaling from the various car-barns of a street-railway system to the central office of such system. The information which it is desired to convey 15 in such systems may comprise, for instance, the following details: the number of a car which has started or is about to start from a given barn, the number of the conductor in charge thereof, and the trip-number of the 20 car.

As the reports from the various barns are made at short intervals and may often occur simultaneously, the conveyance of this intelligence by telephone would require the presence 25 at the central office of a number of telephone operators to receive and record the multitudinous messages. If, on the other hand, ordinary telegraphic apparatus be employed, even though the receiving element at 30 the central office be automatic, it is still necessary that at each barn there should be a skilled telegraph operator capable of transmitting the messages.

The economical object of my invention is 35 to provide a telegraphic apparatus having an automatic receiving element and having a transmitting or sending element, which, while it affords the necessary variety of signals, shall be so simple in its method of manipulation as to require no telegraphic skill whatever 40 on the part of the sender. Thus any ordinary workman who can read numbers is competent to transmit messages which will comprehend all the required information.

45 As it may be desirable to employ an apparatus in conjunction with a telephone-line between the barn and the central station, (in order to permit verbal conversation, where the transmission of other than the ordinary 50 messages may be necessary,) I have shown and described the system so organized that a portion of the telephonic circuit is utilized for the telegraphic connection.

In order to avoid confusion in nomenclature between the elements of the telephone 55 system and those of the special or telegraphic system of my invention, I shall designate the former by the usual terms, such as "transmitter," "receiver," &c., and the corresponding elements of the latter by the terms 60 "sender" and "recorder."

In the drawings, Figure 1 represents diagrammatically such a combined system extending between a single car-barn and the main or central office, it being understood 65 that in practice a number of such systems will be employed to connect with the various barns. Fig. 2 is a front elevation of the sending apparatus, showing a movable member placed in alinement, the others in their normal positions. Fig. 3 is an enlarged horizontal section through a portion of the board. Fig. 4 is a vertical section through the sliding block.

In order to readily explain the general nature of the system shown in Fig. 1, it will be convenient to ignore for the time being the details of the sender and recorder, simply understanding for present purposes that the former is capable of electrically transmitting 75 a plurality of successive signals of definite character by appropriate mechanism and that the latter is capable of recording said signals, as, for instance, upon a paper ribbon.

Referring now to Fig. 1, A indicates the 85 group at the car-barn, and B the group at the central office, C C' indicating the line-wires of the metallic telephone-circuit between the two points, and F the battery. At the group A the telephone is shown as ordinarily constructed, the transmitter thereof being indicated at a, the receiver at a', and the spring-hook for the latter at a''. The contact-terminal for the hook in its released position is shown at a³, the call-bell at a⁴, and the condenser for operating said bell at a⁵.

At the other end of the line b indicates the telephone-receiver, b' the transmitter, b² the magnet of a relay whose armature b³ is adapted to close a local circuit from a battery f, so 90 as to energize a signal-lamp b⁴.

A magneto-electric machine f' is provided for signaling to the other end of the line, an ordinary switching device to throw the same into and out of circuit being indicated at b⁵. 105 All these parts are represented conventionally,

and the system thus indicated may of course be varied in any desired manner.

From convenient points of the main telephone-circuit shunt-wires D D' lead at the 5 respective ends of the line to the special or telegraphic apparatus characteristic of my invention, the "sender" of which is indicated by the group of elements at E and the "recorder" by the group at E'. From the 10 proper elements at each end of the line wires G G', respectively, lead to the ground.

A switch d may be provided, whereby the telegraphic system can be thrown out of circuit, if desired.

15 When the telephone-line is to be used as such, the removal of the receiver a' from its hook a² permits the closing of the circuit at a³ and by means of the relay b² gives the signal for telephone conversation by the illumination of the lamp b⁴. Similarly, when it is desired to telephone from the central office at B to the barn at A, the magneto f' being actuated, with its switch b⁵ in proper relation, the bell a⁴ will be rung by reason of the 20 action of the condenser a⁵, whereupon the talking-circuit can be utilized in the ordinary way. It will be understood, however, that the above-described embodiment is only typical and has thus been set forth because 25 it represents an obvious and convenient adjunct to the system.

Referring now to the special or telegraphic apparatus characteristic of my invention, its main elements are a sender and a recorder. 35 The latter of these two may be an ordinary Morse instrument having a paper ribbon, which is kept constantly moving by clock-work or other convenient device and provided with an element capable of producing 40 upon the paper marks whose length and relation to one another have a predetermined significance and which are in accordance with the currents successively transmitted from the sender.

45 The details of the sender will now be described by reference to Figs. 2, 3, and 4, the instrument being adapted for the transmission of three sets or groups of signals.

K is the base-board upon which the sending instrument is mounted.

55 L, L', and L² are stationary conducting members secured to the base-board, each of these members being provided with raised portions representing predetermined and definite words, as designated at M, which raised portions I call "bars," and at the right of each of these members are arranged a certain number of movable conducting members N, each of these movable members being also 60 provided with raised portions which may be conveniently described as "dots" and "dashes," the dot being approximately one-half the length of the dash and the dash, say, one-half the length of the shortest bar upon

the stationary members. The dots range in 65 value from one to five, designating the numerals "1," "2," "3," "4," and "5," and the dashes range in value from six to ten, designated by the numerals "6," "7," "8," "9," and "0," but whereas the raised portions 70 on the stationary members are arranged in one line each group of raised portions designating a numeral on the movable members is given a separate line thereon.

The movable members are guided in suitable guideways, as represented at O, and are normally held upward by springs or weights P.

Arranged upon the base-board K, directly beneath each of the movable members N, are pins or hooks Q, in number equal to the number of groups of raised portions on the member N, each group designating one of the numerals "0" to "9," inclusive.

R represents connections extending from the movable members and terminating with 85 an eyelet or other means to be secured to one of the pins or hooks Q, so as to hold the member in proper operating position.

The bars M on the surface of the stationary members L, L', and L² are arranged in a 90 straight line with one another.

S is a traveling contact or block carrying a contact-spring S', designed to come in contact with the bars M and also with one of the contact groups upon the movable members 95 when said movable members are arranged in such a position that the contact group will come in alinement with the path of travel of the contact-spring S'. The block S is guided in its movements by the rails or tracks T, and thus it will be seen that by raising or lowering any of the contact members N any line of contact groups upon each of these movable members may be made to come into contact with the contact-spring S', and as each line 100 of contacts upon these movable members represent a different numeral any combination of numbers can be made by the proper manipulation of the same.

105 U is an arm adapted to be controlled by the usual ratchet or step-by-step movement, and this arm is normally held at the right-hand side of the sending instrument by the spring V. The upper end of this arm passes through a sleeve W, swiveled to the block S, 115 and therefore while the arm U describes an arc of a circle in its movement it will cause the block S to move in a straight line, as the sleeve W will slide upon the arm U and the block will be actuated between the rails T. 120

When the sender is to be operated, the arm is pulled toward the left-hand side of the instrument to the position as shown in Fig. 2. Then as the arm is released the spring V will act to force the arm toward the right-hand side 125 of the machine, and the contact-spring S will pass over the bars and contact groups in alinement with said bars.

To the binding-post Y' is connected the terminal of the wire D. An electrical contact between said binding-post and the conducting-arm U is afforded by means of the 5 switch-piece Y, adapted to bear with one end against one of the surfaces of the lower portion of the arm U. When the arm U is swung to the left-hand side, as illustrated in Fig. 2, the frictional engagement of the 10 switch-piece Y with the lower surface of the arm will cause this switch-piece to follow the movement of this arm, thus throwing the lower portion out of contact with the terminal Y'. Hence there is no electrical connection 15 between said arm and said terminal during the period of movement of the arm in said direction; but upon the return movement of the bar the frictional engagement with the switch-piece Y will at once bring the 20 lower part of said switch-piece into electrical contact with the binding-post Y' and will maintain said contact during the whole period of movement of the arm U in that direction. It will thus be seen that when the arm 25 U is in the first instance swung to the left across the faces of the bars, dots, and dashes no circuit will be established; but on the return movement of said arm a circuit will be established with the wire D during the 30 periods of contact between the contact-spring S' and the bars, dots, and dashes then situated in the line which it traverses.

The bars, dots, and dashes having a predetermined significance, it is obvious that any 35 signals within the range comprehended by the various groups upon the stationary as well as movable members can be transmitted and recorded. In the signal system the dots may stand, according to number, for the numerals "1," "2," "3," "4," and "5" and the dashes for the numerals "6," "7," "8," "9," and "0."

As stated at the beginning of this specification, I have illustrated my invention as more 45 particularly adapted for the use of signaling between railway-barns and their center. It is customary for the person in charge of starting the cars on their respective routes to signal the number of the car, the number of the 50 conductor in charge of said car, and the number of the run or trip of said car to the superintendent at the central office. As an illustration, let us suppose that the large bar M designates the word "car" and the contact 55 groups on each of the following movable members indicate one of the numerals "1," "2," "3," "4," "5," "6," "7," "8," "9," and "0," and let us suppose that the first movable member adjacent to said stationary 60 member is pulled downward, so that the group of contacts consisting of only one dash comes in alinement with said bar, as is illustrated in Fig. 2. Then it is obvious that the spring S' in traveling over this bar and dash

will indicate at the receiving-station that car 65 No. 6 has just been sent out. The second stationary member is provided with two bars which may designate the word "conductor," and therefore any of the numeral contact groups placed in alinement with said two bars 70 will give the number of the conductor of said car when the spring S' travels over the same. The third stationary member is provided with three bars, which may designate the word "run" or "trip," and therefore any of the 75 numeral contact groups placed in alinement with these three bars will give the number of the run or trip of said car when the contact-spring S' travels over the same.

To manipulate the movable members so 80 that the proper numeral should come in alinement with the proper word or bar, it is only necessary to pull the member downward and secure the ring or other means on the hook having the desired numeral placed opposite 85 thereto. The person who sends the message need therefore only have intelligence and skill sufficient to understand the numbers which correspond to the dots and dashes and the proper places to secure the respective 90 contact groups. It will thus be seen that a telegraphic message comprising all the information within the necessary scope can be transmitted by a person who has no skill as a telegraph operator, since all that he has to do is 95 to pull down the proper movable members and secure them in their respective places and then move the contact-arm across the proper region.

As stated before, the recording apparatus 100 may be of any of the well-known types adapted to receive and record signals of the "bars," "dash," and "dot" character. Hence to avoid prolixity no detailed description of this element is given.

It is obvious that the different members, stationary as well as movable, have to be in electrical contact with each other. So, also, is it obvious that the base-board may consist of an insulating material; but should the same 110 consist of a conducting material the arm, as well as the switch-piece and binding-post, should be insulated therefrom. It is also obvious that the different members should not only be in electrical contact with each other, 115 but should also be in electrical contact with the ground-wire G.

Having now described my invention, what I claim as new, and desire to secure by Letters Patent, is—

1. In telegraphy, a sending instrument consisting of stationary members and movable members, the stationary members provided with characters designating words or sentences and the movable members provided with characters designating numerals, and a switching arrangement adapted to make electrical contact with said characters 125

in combination with means whereby through the movements of said switching arrangement in one direction the line-circuit is made and through the movement of said switching arrangement in the opposite direction the line-circuit is broken.

2. In telegraphy, a sending instrument, said sending instrument consisting of stationary members having upon their faces contact portions of predetermined and definite character, movable members between said stationary members, said movable members also having upon their faces contact portions of predetermined and definite character, said movable members provided with means to adjust their position as to the stationary members and a contact device adapted to traverse the region of said contacts and establish a circuit therewith said contact device provided with means whereby its circuit with the line is established through the movement in one direction and is broken through the movement in the opposite direction.

3. In telegraphy, a sending device consisting of one or more stationary members provided on their faces with contact portions, one or more movable members between each of said stationary members, each of said movable members provided on its face with contact portions designating the numerals 0 to 9 inclusive, means to adjust their positions as to the stationary members and means to contact said portions and establish a circuit therewith.

- 35 4. In telegraphy, a sending instrument comprising a member provided with one contact-line of predetermined and definite character on its surface, and a second member provided on its surface with a series of contact-lines, each of said contact-lines representing a numeral, the numeral of one line differing from the numeral of the other lines, and means to adjust the relative positions between said two members in a manner so that the one contact-line of the one member should be in alinement with the contact-line of the second member representing the desired numeral, and means to traverse the region of said contact-lines now in alinement and establish a circuit therewith.

- 55 5. In a telegraphic sending device, a traveling contact consisting of an arm or lever pivotally secured at one end and provided with means at the other end to convert its rotary motion into a linear motion, thereby making contact with contact-points arranged in a straight or linear position and an automatic movable switch adapted to make contact with the line of transmission at the movement of the traveling contact in one direction and adapted to break said contact at the movement of the traveling contact in the opposite direction.

6. In a telegraphic sending device, the

combination of a plurality of stationary members having upon their faces contact portions of predetermined and definite character, movable members inserted between said stationary members, and having also upon their faces contact portions of predetermined and definite character, and a movable arm arranged to traverse the region of said contact portions and establish a circuit therewith.

7. A telegraphic sender embracing the following instrumentalities: a supporting-base, a series of stationary members on said base, provided each with raised characters, a series of movable members between said stationary members, provided each with a series of lines of raised characters, means to hold said movable members in one position, means to bring said movable members in a second position, means to secure said members in said second position, and means to electrically connect one or the other of said raised portions with an electric circuit.

8. In a telegraphic sender, a series of movable members, each of said movable members provided with a series of lines of raised characters, each of said lines designating a numeral of different value.

9. As a means to transmit the notice of starting a car, an automatic telegraphic sender embracing the following instrumentalities: a stationary member provided with contact portions designating the word "car" and movable members in proximity thereto designating the number of said car; a stationary member provided with contact portions designating the word "conductor" and movable members in proximity thereto designating his number; a stationary member provided with contact portions designating the word "run" and movable members designating the number of same, and a traveling contact adapted to make circuit through said contacts.

10. In an automatic signaling device adapted to convey intelligence of a predetermined character, a support, a series of elements, the raised contact portions of which are normally in the path of travel of a traveling contact, a second series of elements, the raised contact portions of which are normally out of the path of said traveling contact, means to bring one or the other of said raised portions in the path of travel, means to secure the same in said position, and a traveling contact adapted to automatically traverse the region of said portions and make circuit through the same.

11. An automatic signaling device adapted to convey intelligence of a predetermined character consisting of a series of independent conductors, each of said conductors provided with raised portions designating predetermined letters, numbers or words, a sup-

port for said conductors, adjusting means for
said conductors, a traveling contact adapted
to make circuit through said raised portions
and automatic means to electrically con-
nect and disconnect said traveling means
from the remaining circuit.

5 In testimony whereof I hereby sign my

name, in the presence of two subscribing wit-
nesses, this 26th day of January, A. D. 1903.
